(57) CLAIM

The ornamental design for an automobile body, toy replica and/or other replicas as shown and described.

DESCRIPTION

FIG. 1 is a front and right perspective view of an automobile body, toy replica and/or other replicas, showing our new design;

FIG. 2 is a rear and right perspective view thereof;

FIG. 3 is a right side elevation view thereof;

FIG. 4 is a left side elevation view thereof;

FIG. 5 is a front elevation view thereof;

FIG. 6 is a rear elevation view thereof; and,

FIG. 7 is a top plan view thereof.

The bottom view is omitted and not claimed as part of the claimed design.

The claimed design is indicated by the relatively dark portion in the figures, while the relatively light and deemphasized portions are environmental and form no part of the claimed design.
